UNITED STATES PATENT OFFICE.

FRANK H. WOOLF, OF CHICAGO, ILLINOIS, ASSIGNOR TO HERBERT LEWIS HILDRETH, OF BOSTON, MASSACHUSETTS.

HONEYCOMB-CANDY MACHINE.

1,143,564.

Specification of Letters Patent. Patented June 15, 1915.

Application filed June 22, 1910. Serial No. 569,252.

To all whom it may concern:

Be it known that I, FRANK H. WOOLF, a citizen of the United States, residing at Chicago, in the county of Cook and State 6 of Illinois, have invented a new and useful Honeycomb-Candy Machine, of which the following is a specification.

My invention relates to candy machines which mix or knead a batch of candy preparatory to permitting the candy to set and cool, and the objects of my improvements are, first, to constantly manipulate the batch of candy while it is supported on suitable carrier rods; second, to provide a 15 plurality of stationary rods to coöperate with a plurality of moving rods; third, to force air between the strands of the batch of candy while it is being manipulated; fourth to make a simple, durable and efficient device and other features to become apparent from the description to follow.

The machine comprises two stationary horizontal rods and two horizontal rods arranged to describe a circle about a horizontal axis in such manner that they will pass between the stationary rods alternately once during every cycle of their movement. One of the stationary rods is preferably made hollow and provided with small perforations so that air forced into the hollow rod will pass between the strands of candy as the same is being pulled over the rod. One of the stationary rods is mounted so that it will yield under sufficient pressure in a direction away from the other stationary rod and thus prevent the possible breakage of some part of the machine.

To describe my invention so that others versed in the art to which it pertains can make and use the same I have illustrated it on the accompanying sheet of drawing forming a part of this specification, in which:

Figure 1, is a side elevation of a machine embodying my invention and Fig. 2, is an end elevation of the same.

Similar reference characters refer to similar parts throughout.

Mounted rotatably in a suitable frame 3 is the hollow shaft 4 having rigidly mounted on its one end the cross arm 5 which has rigidly secured to its diametrically opposed extremities the rods 6 which lie parallel to the axis of the shaft 4. Rigidly mounted 55 on the other end of shaft 4 is the large gear

wheel 7 meshing with the small gear 8 mounted rigidly on the shaft 9 which is rotatably mounted in frame 3. Suitable mechanism is provided in connection with shaft 9 to rotate the same, as for instance the clutch 10 and loose pulley 11. It will be understood that when the shaft 9 rotates the rods 6 will travel in a circle about the axis of shaft 4.

Extending longitudinally through the hollow shaft 4 and fitting loosely therein is the shaft 12 having its end adjacent the gear 7 rigidly secured in the frame 3 by set screws 13 or otherwise. The other end of shaft 12 extends a short distance beyond the cross arm 5 where it has rigidly secured thereto the arm 14 provided on its extremity with the rigid rod 15 lying in the same vertical plane with, and parallel to, the rods 6; but not in the circular path of said rods 6 so that the rod 15 is fixed in its position close to the circular path of the rods 6 as clearly seen in Fig. 2. A fourth rod 16 is mounted to lie in the same vertical plane with, and parallel to, the rods 6 and 15, and is preferably arranged outside the circular path of rods 6. It will be noted that in the drawing the rods 6 are arranged equal distances out from the center of their circular path so that both rods 6 travel in the same circular path which on the left as viewed in Fig. 2, lies between the rods 15 and 16, but these rods 6 may be arranged at such distances from the center of their circular paths that the path of the one will be between the rods 15 and 16 while the path of the other will be to the left of rod 16 as viewed in Fig. 2.

The rod 16 is made hollow and is provided with a row of perforations on its upper side through which air forced into the hollow rod escapes and passes upward between the strands of candy which are formed by the rods 6 moving in their circular path in the direction indicated by the arrow in Fig. 2. The hollow rod 16 may be secured in its position rigidly but I prefer to mount it so that it can under sufficient pressure move away from the rod 15 and to this end I mount it on the free end of arm 17 pivotally secured to frame 3 at 18 and yieldingly held in position to the right as viewed in Fig. 2, by the spring 19, being limited in its said movement to the right by the adjustable screw 20. Compressed air from any

suitable source is conducted to the hollow rod 16 through the pipe 21. A screw plug 22 is provided in the end of rod 16 which can be removed for the purpose of cleaning out the hollow rod 16 when necessary.

In operation a suitable batch of candy is laid in position on the rods 15 and 16 and then the power is coupled to shaft 9 which causes the rods 6 to constantly travel in their circular path in the direction indicated by the arrow in Fig. 2. The batch of candy is partly picked up and pulled upwardly in an arc above the rods 15 and 16 each time one of the rods 6 passes up between and past said rods 15 and 16 and the air from the hollow rod 16 passes up between the strands of candy. The batch of candy is thus constantly manipulated while being supported upon the rods 6, 15 and 16. After the batch of candy has been thus manipulated sufficiently, the power is shut off, the candy is removed by hand and a fresh batch of candy is placed on the rods as above described.

Having thus fully described my invention what I claim as new and desire to secure by Letters Patent of the United States is:

1. In a candy pulling machine, the combination of a plurality of candy supporting arms, arranged to move in predetermined paths, means for moving said arms in said predetermined paths, a hollow non operated candy supporting arm provided with perforations and parallel to and located adjacent the paths of said movable arms, and means for forcing air through the perforations of said supporting arm.

2. In a candy pulling machine, the combination of a plurality of movable candy supporting arms, a hollow non operated candy supporting arm having perforations therein, means for moving said movable arms toward and away from said supporting arm and means for forcing air through said supporting arm.

3. In a device of the class described, a plurality of rods mounted to move about a center in a vertical plane, means to move said rods, a stationary rod close to the path of said first named rods and in the same vertical plane therewith and a second rod close to the path of said first named rods

and in the same vertical plane therewith mounted to yield under pressure in a direction away from said first named stationary rod.

4. In a device of the class described, a hollow supporting means provided with perforations retained in a horizontal plane, means for forcing air through the perforations, a second supporting means retained in position parallel to said first named supporting means, a plurality of pulling means and means for moving the pulling means past the supporting means and above and below the same.

5. In a device of the class described, a plurality of pulling rods arranged to travel laterally about a center in a vertical plane, a hollow horizontally disposed supporting rod provided with perforations located outside the path of the first named rods, means for forcing air through said perforations, a horizontally disposed supporting rod located within the circular path of the first named rod and means for moving the pulling rods past the supporting rods.

6. In a device of the class described, a suitable frame, a hollow shaft rotatably mounted in said frame, a stationary shaft extending through said hollow shaft, a horizontally disposed supporting means secured to said stationary shaft, a plurality of pulling means mounted on said hollow shaft, and means for moving said pulling means past said supporting means and above and below the same.

7. In a device of the class described, pulling rods arranged to move laterally about a center in a vertical plane, a supporting rod mounted parallel to said rods and in the same vertical plane therewith, arranged to yield under pressure and means for moving said rods.

In testimony whereof I have signed my name to this specification in presence of two subscribing witnesses this 16th day of June 1910 at Chicago, Illinois.

FRANK H. WOOLF.
